I claim the ornamental design for an adjustable wall mounting system, substantially as shown and described.

DESCRIPTION

A portion of the disclosure of this patent document contains material that is subject to copyright protection. The copyright owner has no objection to the facsimile reproduction by anyone of the patent document or patent disclosure as it appears in the Patent and Trademark office, patent file or records, but otherwise reserves all copyright rights whatsoever.

FIG. 1 is a front top right perspective view of an adjustable wall mounting system, showing my new design;

FIG. 2 is a front left perspective view thereof;

FIG. 3 is a rear top right perspective view thereof;

FIG. 4 is a front bottom right perspective view thereof;

FIG. 5 is a front elevation view thereof;

FIG. 6 is a left elevation view thereof, the right side being a mirror image thereto;

FIG. 7 is a rear elevation view thereof; and,

FIG. 8 is a bottom plan view thereof; the top side being a mirror image thereto.
